RECOIL LOADING FIREARM

Thomas Frederick Sanders, Slough Trading Estate, England, assignor to Sanders Small Arms, Limited, London, England

Application February 23, 1937, Serial No. 127,239
In Great Britain February 26, 1936

8 Claims.

(Cl. 42—4)

The invention relates to recoil loading firearms and is directed to means for locking and unlocking the breech bolt at the appropriate times. It is applicable equally to firearms of the type in which the movements of the locking member are controlled by an inertia member which lurches forward in relation to the gun on the recoil, and to those of the type in which the breech casing and barrel together recoil on a fixed support, the relative movement of the recoiling parts and support controlling the action of the locking member.

According to the present invention a locking member is pivoted on the breech casing on a substantially central axis perpendicular to the longitudinal axis of the gun and makes contact by a lateral surface with an abutment provided on a part which does not at first participate in the recoil. The last-named part may be an inertia member capable of sliding longitudinally in relation to the breech casing or it may be a support on which the gun is mounted to recoil against resilient means.

Two embodiments of the invention will be described by way of illustration in conjunction with the accompanying drawings wherein:—

Figure 1 is a plan of part of the breech casing of a repeating rifle omitting parts which are not relevant to the present invention;

Figure 2 is a sectional elevation of the same;

Figure 3 is a section taken on the line III—III of Figure 2;

Figure 4 is an inverted plan partly in section of the inertia member in the locking position;

Figure 5 is a corresponding view in the unlocking position;

Figure 6 is an end view of the locking member;

Figure 7 is a sectional elevation of the parts assembled;

Figure 8 is a sectional elevation of part of a sub-machine gun, again omitting parts not relevant to the present invention;

Figure 9 is a corresponding plan of the same;

Figure 10 is a sectional end elevation of the same;

Figure 11 is an inverted plan showing the locking member in the locking position, and

Figure 12 is a similar view in the unlocking position.

Referring first to Figures 1 to 7 a breech casing 1 is provided with longitudinal grooves 2 for guiding a breech bolt 3 in its normal travel rearwards under the influence of the gases and forward again due to the usual recuperator spring

(not shown). A cylindrical turret 4 on the breech casing fits a recess 5 in a locking member 6 and thus constitutes a pivot for the locking member. The outer part of the locking member is generally cylindrical but with parts cut away, leaving an incomplete skirt projecting downwards to embrace the cylindrical turret 4. The locking member 6 is provided with a forward projecting lug 7 abutting against a step 8 on the bolt 3. This is clearly seen in the locking position in Figure 4 and in the unlocking position in Figure 5.

A diametral groove 9 is cut right across the skirt of the locking member so that when the latter is rotated to the unlocking position of Figure 5 a clear run is provided for the bolt, the lug 7 then also having moved aside to clear the step 8. The pivoting of the locking member is controlled by an inertia member 10 which will now be described.

The inertia member 10 is capable of sliding in a longitudinal direction on the breech casing 1 and is formed as a cover with top and two sides over the breech mechanism, while its ends are open to give freedom of longitudinal movement. The depending sides of the cover 10 embrace the locking member 6 and carry the actuating means for it.

A blade spring 11 is attached to one depending side of the cover 10 and presses against a flat formed on one side of the locking member 6 by cutting away some of the cylindrical part. The flat is so located that the tendency of the spring 11 is to keep the locking piece 6 in the locking position. This may be clearly seen by comparing Figures 4 and 5.

On the other side of the locking piece 6 a recess is formed to co-operate as shown with a pin 12 projecting inwards from the depending side of the cover 10 opposite to that carrying the spring 11.

When the gun is fired the recoil causes the inertia cover 10 to move forward in relation to the gun 1, that is to the left in Figures 4 and 5, with the result that the pin 12 makes contact with the side of the recess in the side of the locking piece 6, the latter being only capable of a pivoting movement in relation to the breech casing 1, and thus rocks the locking piece to the unlocking position of Figure 5. Any further movement is prevented by the side of the recess in the locking member coming into contact with the hump 13 formed on the inside of the cover 10. The locking member is thus stopped in its pivoting movement at a position in which the groove 55

9 is exactly in register with the runway for the bolt 3 in the breech casing 1.

After the bolt has passed the locking member on its return journey the spring 11 restores the locking member 6 to the locking position as the inertia cover 10 goes back to its normal position.

Where the inertia member is replaced by a stand or support on which the gun recoils, some modification is required in the arrangement as 10 may be seen from the embodiment shown in Figures 8 to 12, which will now be described.

A sub-machine gun comprises a stand or support 14 with trigger guard 15 and magazine 16. The breech casing 1 is mounted to slide on the 15 support longitudinally by tongues and grooves 17. The recoil is taken by a buffer 18 between the front end of the support 14 and a suitable part of the breech casing. The buffer 18 restores the breech casing together with the barrel (not 20 shown) and other parts attached to it to the firing position after recoil.

The bolt 3 is of square section at its rear end with a recess 19 to accommodate the end of the recuperator spring 20. A step 8 is formed on the 25 square part of the bolt to engage a lug 7 on the front of the locking member 6. As before the locking member 6 is of cylindrical form with the lug 7 projecting in front. It is seated in a recess 21 in the upper part of the breech casing which, 30 with the assistance of a screwed pin 23, serves as a bearing. The front face of the lug 7 is made concentric with the locking member and the step 8 is hollowed slightly to fit it.

A blade spring 11 as before engages a flat 22 35 formed on the side of the locking member and tends to rotate the latter into the locking position of Figure 11. The locking member is provided with a groove 9 which registers with a corresponding groove 24 in the breech casing when 40 the member is in the unlocking position of Figure 12, so as to allow the bolt free passage to the rear.

The support 14 is provided with an upward projecting part 25 carrying a pin 26 and the locking member 6 has a downward projecting pin 27 located to make contact with the pin 26. In the locked or firing position the pins 26 and 27 are almost or quite in contact.

As the breech casing recoils on firing, the engagement of the pins causes the locking member 50 6 to rotate until on the full compression of the buffer 18 the groove 9 registers with the groove 24. The lug 7 has then moved away sideways from the step 8 and the bolt 3 is free to execute its rearward movement for the purpose of reloading. 55 The breech casing is held in the recoiled position by a detent (not shown) during this rearward travel of the bolt. The recuperator spring 20 then returns the bolt to the firing position, the bolt trips the detent and the blade spring 11 returns the locking piece 6 to the locking position so that all parts are now ready to fire the next shot.

Various modifications may be made to the 65 weapon described within the scope of the invention. For instance where an inertia member is used provision may be made for the latter to travel forward a greater or less distance before making engagement with the locking member. 70 In this way any weapon may be made suitable for the ammunition to be used with it, so that the bolt lock is retained during the requisite amount of time for the best operating conditions. Actual adjustment of the distance in question could be 75 provided on a gun, but in general it is to be re-

garded as a factor at the disposal of the manufacturer in preparing his detailed designs.

Moreover the inertia member, instead of being formed as a cover over the breech mechanism, might be located inside the breech casing and then a slight modification would be required to other parts described above. Another modification would be to use an anti-friction roller between the inertia member and the inclined surface of the locking member; the last-named surface may 10 be a part of a rib provided on the locking member; or the pivot axis of the locking member may be offset a little laterally from the axis of the gun.

What I claim is:—

1. A bolt locking arrangement for a recoil loading firearm comprising a breech casing, a part not participating initially in the recoil, longitudinal guiding means between the said part and the breech casing, a breech bolt slidably mounted in the breech casing, a bolt locking member pivoted on the breech casing on a substantially central axis perpendicular to the longitudinal axis of the gun, and a lateral surface on the locking member located to contact with the part not participating initially in the recoil and so rocks the locking member.

2. A bolt locking arrangement for a recoil loading firearm comprising a breech casing, a part not participating initially in the recoil, longitudinal guiding means between the said part and the breech casing, a breech bolt slidably mounted in the breech casing, a bolt locking member pivoted on the breech casing on a substantially central axis perpendicular to the longitudinal axis of the gun, a lug projecting forwards on the locking member to make contact in the locking position with a step on the bolt, and a lateral surface on the locking member located to contact with the part not participating initially in the recoil and so rock the locking member.

3. A bolt locking arrangement for a recoil loading firearm comprising a breech casing, a part not participating initially in the recoil, longitudinal guiding means between the said part and the breech casing, a breech bolt slidably mounted in the breech casing, a bolt locking member pivoted on the breech casing on a substantially central axis perpendicular to the longitudinal axis of the gun, a groove being provided on the underside of the locking member which registers with corresponding parts of the breech casing when in the unlocking position to provide a free passage for the bolt, and a lateral surface on the locking member located to contact with the part not participating initially in the recoil and so rock the locking member.

4. A bolt locking arrangement for a recoil loading firearm comprising a breech casing, an inertia member, longitudinal guiding means between the inertia member and the breech casing, a breech bolt slidably mounted in the breech casing, a bolt locking member pivoted on the breech casing on a substantially central axis perpendicular to the longitudinal axis of the gun and having a depression in its side, and an inward projection on the inertia member located to make contact with the depression in the side of the locking member.

5. A bolt locking arrangement for a recoil loading firearm comprising a breech casing, a support for the gun, longitudinal guiding means between the breech casing and the support, a breech bolt slidably mounted in the breech casing, a bolt locking member pivoted on the breech casing on a substantially central axis perpendicular to the

longitudinal axis of the gun, a downward projection on the locking member located laterally in relation to the pivot axis and an upward projection on the support located to contact with the 5 downward projection on the locking member on the recoil.

6. A bolt locking arrangement for a recoil loading firearm comprising a breech casing, a part not participating initially in the recoil, longitudinal 10 guiding means between the said part and the breech casing, a breech bolt slidably mounted in the breech casing, a bolt locking member pivoted on the breech casing on a substantially central axis perpendicular to the longitudinal axis of the 15 gun and having a flat on one side thereof and an engagement surface on the other, a blade spring on the breech casing located to engage the flat and normally hold the locking member in the locking position, the engagement surface of the 20 locking member being located to contact with the part not participating initially in the recoil.

7. A bolt locking arrangement for a recoil loading firearm comprising a breech casing, an inertia member, longitudinal guiding means between the 25 inertia member and the breech casing, a breech bolt slidably mounted in the breech casing and provided with a step facing rearwards, a bolt locking member pivoted on the breech casing on a substantially central axis perpendicular to the 30 longitudinal axis of the gun and provided with a groove on its under side to register with corresponding parts of the breech casing when in the

unlocking position to provide a free passage for the bolt, a lug projecting forwards on the locking member to make contact in the locking position with the step on the bolt, the locking member also being provided with a flat on one side and a depression on the other, a blade spring on the breech casing located to engage the flat on the side of the locking member and hold the latter normally in the locking position, and an inward projection on the inertia member located to make contact 10 with the depression in the side of the locking member.

8. A bolt locking arrangement for a recoil loading firearm comprising a breech casing, a support for the gun, longitudinal guiding means between the breech casing and the support, a breech bolt slidably mounted in the breech casing and provided with a step facing rearwards, a bolt locking member pivoted on the breech casing on a substantially central axis perpendicular to the 15 longitudinal axis of the gun and provided with a flat on its side and a groove on its under side to register with corresponding parts of the breech casing when in the unlocking position to provide a free passage for the bolt, a lug projecting forwards on the locking member to make contact in the locking position with the step on the bolt, and a blade spring on the breech casing located to engage the flat on the side of the locking member and hold the latter normally in the locking position. 20 25 30
